CIGARETTE PACKAGE

Bruce McPherson, Greenville, S. C.

Application November 30, 1934, Serial No. 755,492

1 Claim. (Cl. 206—48)

This invention relates to containers for cigarettes, cigarette packages or the like and it is an object of the invention to provide a novel container adapted to be folded about a package of 5 cigarettes for protecting the same against crushing or damage when carried in the pocket of the user and at the same time provide matches for lighting the cigarettes.

The invention is a further development of the 10 invention disclosed in my patent, #1,944,098, and my application S. N. 717,839, filed March 29, 1934.

Referring to the accompanying drawing which is made a part hereof and on which similar reference characters indicate similar parts;

15 Fig. 1 is a perspective illustrating one application of the invention in its operative position;

Fig. 2, a plan view of the blank of Fig. 1;

Fig. 3, a plan view of a modified container blank;

20 Fig. 4, a perspective of the container of Fig. 3 partly folded;

Fig. 5, a plan view of a further modified container blank;

25 Fig. 6, a side elevation of a container folded from the blank of Fig. 5 but with a match card stitched thereto;

Fig. 7, a perspective of a further modified two-part container, with the parts separated;

Fig. 8, an assembled view of the container of 30 Fig. 7 with a match card glued thereto, and

Fig. 9, a plan view of the blank of the inner portion of the receptacle of Fig. 7.

Referring to the drawing, as shown in Fig. 1 a 35 package of cigarettes 10 is enclosed by a container of the character exemplifying one application of the invention.

The container has a match packet 11 attached thereto and such container is formed of a blank having parallel crease lines 12 forming the back 40 13, front 14 and sides 15 and 16 of the rectangular container formed by the folded blank. The free edge of the side 16 has an integral gluing strip 17 which underlies the edge of the front 14 when the parts are glued together to form a 45 hollow rectangular body.

The blank is further provided with crease lines 18 and 19 to form a windowed closure 20 for one end of the container and to form a partial closure 21 for the other end of the container, the partial 50 closure affording an opening through which the cigarette package is exposed and consequently through which the cigarettes may be removed. That portion 22 of the blank between the crease lines 18 and 19, when the blank is folded to form 55 the container, lies within the container behind

the front 14 and the cigarette package. The free end of the blank 23 adjacent the crease line 19 is tapered to form a tab which also is intended to extend within the container to secure the section 21 in place over a portion of the end of the cigarette package. A slit or slot 24 is provided in the back 13 through which the tab 23 may be inserted. 5

In order to attach a packet of matches slots or slits 25 are provided in the front 14. The packet of matches 11 may be attached to the container 10 by opening the packet and slipping the match covering flap through the slits and then folding the cover flap in a manner to cover the matches.

The blank forming the container just described 15 may be of cardboard or other desired material suitable for the purpose and said blank is made in the shape described by cutting, stamping or in other desired manner.

The above described blank is similar to the 20 blank forming the container disclosed in my patent, #1,944,098 but however, is adapted to have the strip 17 fastened by glue or similar material to the front of the container, the joint being at the corner, instead of providing a blank having front flaps held together by a match packet as 25 described in my patent. Therefore instead of having a longitudinal slot in each flap as in the patent, the slits or slots 25 are provided transversely so that the match packet will be held longitudinally of the container as shown in Fig. 1, 30 instead of transversely of the container as shown in the patent.

It will be readily understood also that the invention is not limited to the location of the joint between the side 16 and front 14, but obviously 35 the same might be placed at any other desired location.

Figs. 3 and 4 show a further modified form of 40 container which, while being substantially the same container as that of Fig. 1 and resembling the blank of Fig. 2, nevertheless, instead of having the portions of the blank which form closures for the ends of the container connected by an additional body portion 22 as in Fig. 2, this portion is eliminated and flaps are connected directly 45 to the back of the container. In this embodiment the blank has crease lines 12' which form a back 13', front 14', and sides 15' and 16'. The back 13' has the flaps formed integrally therewith. 50

The blank of Figs. 3 and 4 is further provided with crease lines 18' and 19' which form end closures 20' and 21', the end closure 20' having a flap 26 for insertion into the container between the front 14' and the cigarette package. Like- 55

wise the end portion 21' is provided with a flap 27 for similar insertion between the cigarette package and the front 14' or optionally through a slit 24'. In this blank a gluing strip 17' corresponds to and is used for the same purpose as the gluing strip 17 in the preceding figure and Fig. 2. A container formed in accordance with the disclosures of Figs. 3 and 4 may be preferable in certain instances and requires less material, since instead of long flaps, it has two short flaps, one forming an end closure flap and the other forming a half closure.

In Fig. 5 is shown a further modified form of container which is similar to the container shown in Figs. 3 and 4. However, instead of the end portions 20' and 21' and associated flaps being both attached to the back as shown in Figs. 3 and 4, the end portions 20'' and 21'' are attached respectively to the portions 13'' and 14'' forming the back and front of the receptacle. In addition, the sides 16'' and 15'' are extended to provide flaps 28 and 29 which cooperate with the portion 20'' of the blank to reinforce one end of the container and assist in forming closures therefor. Otherwise, the construction is similar to that of Figs. 3 and 4, the joint of course being locatable in any position desired.

Figs. 7, 8 and 9 disclose a further modified container of two part construction. In Fig. 9 a blank is provided which when folded constitutes an inner member which is slid into an outer sleeve. The blank of Fig. 9 is provided with crease lines 30 and 31 and 32 dividing the blank into a bottom 33, ends 34 and 35, flaps 36 and 37 and side flaps 38, when the blank of Fig. 6 is folded. As shown in the lower left of Fig. 7 it is adapted to be slid into a receiving sleeve which consists of a rectangular blank provided with crease lines and folded to form a bottom 39, top 40 and sides 41 and 42, the side 42 being provided with a gluing strip 43 which is attached to the top 40. As shown, a cigarette package being placed in the inner member or folded blank of Fig. 9 is slid into the cooperating receiving sleeve forming blank in the manner shown in the extended view of Fig. 7. If desired, the portions 35 and 37 of the blank of Fig. 9 may be made narrower, corresponding in width to the portion 21 of the blank of Fig. 2 to afford an opening through which cigarettes may be removed from the package. The sleeve may have its top 40 provided with slits 44 for reception of a match packet as previously described.

To the container of either of the several figures a match card or match packet may be attached in a number of ways. As shown in Fig. 1 the

match card is fastened to the container by having the flap of the match card inserted through slots in the container. The container represented by other figures of the drawing is constructed with match card receiving slots.

In Figures 1 and 2 it will be noted that the slots 25 for receiving the flap of the match card are straight. However, these slots are preferably made in the form of angular slits as shown at 25' in Figures 3 and 4, 25'' in Figure 5, and 44 in Figure 7. It will be seen that by forming these slots angularly the match card flap is more easily inserted.

In Figs. 6 and 8 containers are shown having match cards 11 attached respectively by stitching 15 and gluing. It will be readily understood that the containers may have the match cards attached in either of the ways suggested or other desired manner.

If desired the end of each container may be 20 provided with a window or an opening by means of which the brand of cigarettes may be seen, the blank of Figs. 2 and 3 having a window 45 and 45', the blank of Fig. 5 having a window 46 and the blank of Fig. 9 having a window 47. 25

It will be obvious to those skilled in the art that various changes may be made in my invention without departing from the spirit thereof and I do not limit myself to what is shown in the drawing and described in the foregoing specification but only as indicated in the appended claim. 30

I claim:

A container for a package of cigarettes comprising a blank foldable to form a hollow substantially rectangular open-ended cigarette 35 package-receiving body in which the cigarette package is slidably receivable, said body having a double-walled side and constructed to fit snugly about the exterior of and substantially enclose the package of cigarettes, said blank further having a portion integral therewith providing foldable closure means for the ends and the double wall on one side of the container, that portion of the blank which forms the closure means for one end of the container being of a width to 45 provide an opening in the container through which cigarettes from the cigarette package therein may be removed, the main body of said blank being provided with a plurality of slots in a single side of the double walled side portion 50 thereof for the reception of a match card, a portion of the match card being located between the walls of said double-walled side of the container when the blank is folded.

BRUCE McPHERSON.
